CEMENT RETAINER

Filed Aug. 9, 1943

UNITED STATES PATENT OFFICE

2,421,399

CEMENT RETAINER

Milo C. Wilson and Vernon D. Davidson, Corpus
Christi, Tex.; said Wilson assignor to said
Davidson

Application August 9, 1943, Serial No. 497,936

1 Claim. (Cl. 166—12)

1

The invention relates to a tool for retaining liquid under pressure in an oil well. In applying liquids under pressure in an oil well, it is necessary that a tool be provided which can be securely anchored in position so as to remain stationary when pressure is applied below it in order to force liquids into the earth formations or to accomplish other functions.

The present invention is in the nature of an improvement over that disclosed in Patent 2,338,370 which was granted to one of the present joint inventors.

With the present cement retainer the structure has been so devised that the anchoring mechanism to hold the retainer in a set position is actuated as a function of the pressure being applied to the tool so that the tendency to anchor the tool increases with the pressure applied to it.

It is one of the objects of the invention to provide a cement retainer to be anchored in a well bore wherein the hydraulic pressure being applied through the retainer tool reacts in the tool to anchor the tool.

Another object of the invention is to provide in a cement retainer a set of slips and a wedging mandrel wherein the mandrel is urged to wedging position by the hydraulic pressure being exerted through the tool.

Another object of the invention is to provide a cement retainer having a mandrel with a slip supporting housing telescoped thereabout wherein the slips will be set when the mandrel and housing are urged apart.

Another object of the invention is to provide a cement retainer wherein a mandrel and slip supporting housing are urged apart to set the slips by the hydraulic pressure applied through the retainer.

Other and further objects of the invention will be readily apparent when the following description is considered in connection with the accompanying drawings wherein:

Fig. 1 is a vertical sectional view of the retainer tool with the slips in retracted position.

Fig. 2 is a section taken on the line 2—2 of Fig. 1 and illustrating the arrangements of the slips and the friction drag springs.

Fig. 3 is a vertical sectional view of the retainer in set position in a well pipe.

Fig. 4 is a side elevation of the cement retainer.

The retainer is made up of a mandrel 2 which is connected to an operating pipe 3 by which the tool may be manipulated in the well bore. This mandrel 2 has an open passage 4 therethrough and is provided on its outer periphery 55

2

with the frusto-conical wedge portion 5. A second such portion 6 is disposed below the first portion. The portion 6 is cut away at 7 to provide the shank or tail piece 8 of the mandrel. 5 This tail piece terminates in an exposed end area 9 and has a plurality of packing or sealing rings 10 affixed about its periphery by having them disposed in the annular recesses 11 about the shank 8. These packings are downwardly facing to seal against pressure moving upwardly thereagainst as seen in Fig. 1.

Telescoped about the mandrel and the tail piece 8 is a housing 15 which carries a pin 16 arranged to be disposed in the groove or slot 17 in the periphery of the mandrel. This slot 17 as seen in Fig. 4 is generally known as an inverted J slot or bayonet joint whereby the housing and mandrel are locked together when the pin is in the position of Fig. 4, but may have relative longitudinal movement when the pin is in the vertical portion of this slot as seen in Fig. 3. In order to manipulate the tool and move the pin 16 to either retain or release the mandrel relative to the housing a plurality of drag springs 18 are carried by the periphery of the housing as seen in Figs. 1 and 2. In Fig. 3 these springs are shown as pressing against the inside of the well pipe 20 so as to tend to hold the housing in any position which it might be in such pipe.

20 The housing has a plurality of openings 21 therein, each of which receives one of the slip members 22 which is arranged for radial movement in and out of the opening 21 so that the teeth 23 on the slip may engage the pipe 20 as seen in Fig. 3. These slips are inserted through the opening and retained in place by a latch bar 24 attached to the outside of the housing.

25 Each of the slips 22 has an inclined face 26 on the back side thereof which is complementary with the frusto-conical surface 5 on the mandrel 2 so that relative longitudinal movement by the mandrel on the one hand and the housing 15 and slips on the other hand causes the slips to move radially. If this movement of the mandrel and the housing is in a direction so that the mandrel and housing move apart, then the slips will be set and when they move toward each other, the slips will be retracted. If the slips become lodged in the opening or against the casing, then the shoulder 28 on the mandrel may engage the upper end 29 of the slip member and knock it loose from its gripping position or the outstanding flange at the top of the mandrel may be so constructed as to strike the upper end of the housing 15 to accomplish the same purpose. The tail piece 30 on the

slips tends to hold them in position against excessive outward movement.

The tool will be lowered into the well bore with the parts shown in the position of Fig. 1. The springs 19 tend to hold the housing in any particular position and a slight rotation thus releases the pin 16 so as to move it into the vertical portion of the slot 17. The operating pipe 3 will now be manipulated to pull upwardly on the mandrel so as to move the wedge portions in behind the slips 21 and set them against the pipe. In this manner the cement retainer is initially anchored.

The housing 15 has a passage 30 therethrough which is enlarged by the tapered shoulder 31 to provide a pressure chamber 32 which, as seen in the drawings, receives the bottom or tail piece 8 of the mandrel with the packings 10 engaging against the surface of the chamber 32 so as to form a seal therewith. The outer surface of the lower position of the housing 15 may be provided with a plurality of rubber cups or packings 35 which are held in position by the retainer collars 36 and the spacer rings 37, all of which are in turn clamped in place by the coupling 38. The contact surface of the upper collar with the shoulder of the housing may be semi-circular faces which are ground to insure a seal to prevent leakage past the packing cups. A length of pipe 39 may extend below the coupling if desired.

With the parts in the position of Fig. 3, cement or other liquid is pumped downwardly through the operating pipe and into the well or against the formation as the case may be. This pressure moves back inside of the pipe 20 and expands the packings 35 to form a seal with the pipe. There is, of course, a tendency of this pressure to move the housing upwardly but the initial upward pull on the operating pipe 3 and mandrel 2 maintains the slips 21 in gripping position due to the tremendous mechanical advantage of the wedge portions on the slips and the mandrel.

In the present retainer, however, it is desired that the initial gripping action of the slips be augmented as a function of the pressure applied to the tool. In other words, a semi-mechanical hydraulic operation is obtained.

When the pressure is exerted through the pipe 3 the passage 4 of the mandrel and the passage 30 in the housing, it seems obvious that this pressure will also be exerted in the chamber 32 and inasmuch as hydraulic pressure is equal in all directions there will be exerted on the lower end 9 of the mandrel a pressure tending to expel the mandrel from the chamber 32 and there will be a pressure against the beveled surface 31 in the housing tending to move the housing away from the mandrel. These two opposite pressures will

be equal as to any unit area and will tend to move the mandrel and the housing apart so that there will be a tendency due to the application of this pressure against the lower end of the mandrel to expel the mandrel and move it away from the housing. This force tends to hold the mandrel beneath the slips and to maintain them in gripping position and of course this force will vary in accordance with the applied pressure so that it may be said that the retainer operates as a function of the applied pressure.

In the housing 15 the enlarged recesses 41 provide ample area for movement of the wedge portions so that they will not become stuck due to the entry of sand or other foreign matter. A space 41 is also provided by the chamber 32 being somewhat larger in diameter than the shank 8 of the mandrel so as to avoid sticking of the parts.

Broadly the invention contemplates a semi-mechanical hydraulically operable cement retainer which is anchored in position as a function of the pressure applied to it.

What is claimed is:

A cementing tool comprising an operating pipe, an open hollow mandrel thereon, a housing about said mandrel, a latch means connecting said housing and mandrel and operable to permit movement of said mandrel relative to said housing, a set of upwardly facing tapered faces on said mandrel, a set of slips carried by said housing, tapered faces on said slips to cooperate with said mandrel faces whereby to move said slips into anchoring position by upward movement of said mandrel relative to said housing and slips to anchor the tool in the well, packer means on said housing to effect a seal therearound upon application of pressure through said mandrel, and means on said mandrel to engage said housing upon relative downward movement so as to knock said housing and slips loose from anchoring position; wherein there is an enlarged chamber in said housing and said hollow mandrel is disposed as a piston in said chamber, there being opposed faces in said chamber.
